UNITED STATES PATENT OFFICE.

CLARE H. DRAPER, OF HOPEDALE, MASSACHUSETTS, ASSIGNOR TO HOPEDALE MANUFACTURING COMPANY, OF MILFORD, MASSACHUSETTS, A CORPORATION OF MASSACHUSETTS.

FEELER LOOM.

Application filed September 22, 1921. Serial No. 502,482.

To all whom it may concern:

Be it known that I, CLARE H. DRAPER, a citizen of the United States, residing at Hopedale, in the county of Worcester and 5 State of Massachusetts, have invented certain new and useful Improvements in Feeler Looms; and I do hereby declare the following to be a full, clear, and exact description of the invention, such as will enable others 10 skilled in the art to which it appertains to make and use the same.

The present invention relates to an improvement in feeler looms.

When the outgoing shuttle thread is severed on the hopper side of the loom, there is 15 a long piece of weft extending from the shuttle eye to the selvage which is liable to be caught in the shuttle box and be drawn into the shed with the new thread from a 20 freshly inserted bobbin. This long thread extending from the exhausted bobbin to the point of parting is difficult to remove from the shuttle eye by the very reason of its length. It is desirable when the exhausted 25 bobbin is forced out of the shuttle that the thread extending from the bobbin to the point of parting be pulled through the eye so as to get it out of the way of the incoming thread to avoid the possibility of its 30 being drawn into the warp. The longer this thread, the greater the liability of its being caught and drawn into the warp.

The present invention is directed to produce a loom construction wherein when the 35 feeler indicates critical exhaustion the thread is cut near the shuttle eye on the opposite side of the loom from the hopper or weft replenishing mechanism. When this thread has been cut on the opposite side of the loom 40 from the hopper, and the shuttle is thrown over to the hopper side, the shuttle lays no thread in the shed, and the next throw of the shuttle carrying the new load of filling should, in order to secure perfect cloth, lay 45 the new thread in the same shed. This is secured, according to the present invention, by stopping the harness motion for a period of one beat of the lay. This is more especially important in looms having more than two 50 heddles and weaving diagonal or other more complicated weaves.

To the above ends the present invention consists in the feeler loom hereinafter described and particularly defined in the 55 claims.

In the accompanying drawings illustrating the preferred form of the invention, Fig. 1 is a plan of the left hand shuttle box and associated mechanism of a left hand loom, that is to say, a loom having its knock-off lever 60 on the left hand side; Fig. 2 is a sectional side elevation of a loom; Fig. 3 illustrates the clutch motion for disconnecting the auxiliary cam shaft from the main cam shaft; Fig. 4 is a side elevation; and Fig. 5 is a 65 front elevation of the parts of the feeler mechanism, weft severing devices and associated parts.

The illustrated embodiment of the invention is described as follows. A feeler F, a 70 latch L and a controller C, are or may be substantially as illustrated and described in the application of Jonas Northrop, filed Aug. 16, 1921, Serial No. 492,733, except as hereinafter stated. The feeler is connected 75 by means of the link 10 with the latch L pivoted at 12 on the latch slide 13, being normally held in inoperative position, as shown in Fig. 1, by the angle portion 14 of the controller stud 15 of the controller C, 80 which angle portion 14 engages the downwardly projecting boss 16 of the latch L. The controller spring 17 normally tends to hold the controller in its rearward position, so as to hold the latch in its inoperative position, and the spring 18 tends to turn the latch into its operative position. The controller C is supported in a groove in the upper end of the weft hammer H, the former being provided with a cam surface which permits the 85 controller to drop in front of the projection 30 on the shuttle box upon those beats of the lay when the shuttle is boxed on the left hand side of the loom. The latch L is provided with a shoulder 19 adapted to be engaged by 90 the knife 20 of the weft hammer H. Upon the indication of critical filling exhaustion, the end of the filling feeler moves along the surface of the bobbin toward the butt under the impulse of the latch spring 18, the latch causing the feeler to move in this direction, and thus the knife 20 of the weft hammer on the next forward beat engages the shoulder 95 19 of the latch and forces the latch slide 13 forward, causing a change boss 21 to engage the right hand end of a knife opening lever 22, thereby swinging the left hand end of the knife opening lever into engagement with the rear end of the knife lever 23, which is 100 105 a bell crank lever pivoted at 24, the lower 110

end of which engages the knife stud 25, and by moving it rearwardly throws the knife 26 down into open position. The knife is closed by the engagement of a leather faced 5 knife operating slide 27 with the shuttle tip, which slide bears the stud 25, and by engagement with the slot in the knife arm, closes the knife.

Thus on the first indication of critical filling exhaustion, the knife is opened ready to 10 cut a filling on the next forward beat of the lay when the shuttle is boxed on the left hand side of the loom. There are two forward beats of the lay with the shuttle 15 boxed on the left hand side at which critical filling exhaustion is indicated. On the first, the knife is opened, and the change arm 31 is lowered ready to be struck by the change boss 21 on the second indication of 20 critical filling exhaustion. On the second forward movement of the latch slide, the shuttle strikes the knife operating slide 27, and causes it to sever the filling running from the selvage to the shuttle. It will be 25 noticed that the length of filling extending from the shuttle eye to the knife is short, and that the thread is clamped extending from the knife to the selvage. On this same forward movement of the latch slide, 30 the change boss 21 strikes the lowered end of the change arm 31, and pushes it forwardly, thereby rocking the change shaft 32 and causing a new bobbin to be inserted in the shuttle on the next shot of the shuttle to the right hand side of the loom. As 35 the change arm approaches the limit of its forward movement, it rides up on the inclined end 33 of the right hand end of the knife opening lever 22, at a time when such 40 right hand end occupies the position shown in dotted lines at 34, Fig. 1. On this forward movement of the change arm 31, the pawl 35, pivoted on the side of the change arm, catches in front of the right hand end 45 of the knife opening lever 22 while it is in the position 34, so that when the latch slide again moves rearwardly, it pulls the knife opening lever back into the position shown in full lines in Fig. 1. The left hand end of 50 the knife opening lever 22, in opening the knife, passes over and beyond the forward inclined end of the knife lever 23, and when it is restored to its original position, as just described, it moves forward again under the 55 inclined end of the knife lever 23, lifting it inoperatively as it passes thereunder. The pawl 35 pivoted on the change arm is normally held up by the spring 36 (see Fig. 4).

60 When the filling has been severed and the end extending from the knife to the selvage is clamped by the knife, it will be seen that the filling thus held by the knife extends in front of the filling fork 50, and being held thereby, it tilts the fork so that the latter is

70 prevented from catching on the weft hammer hook 51, and causing a forward movement of the weft slide 52, which operates to swing the stop lever 53 to engage and trip the knock-off lever 54.

75 On the second forward movement of the latch slide 13, the weft replenishing mechanism is thrown into operation by the turning of the change shaft 32. At the same time the depending lever 37, connected with the change shaft, opens the harness motion clutch on the cam shaft S. This is accomplished by means of the link 40, which is connected at its forward end to the lower end of the depending lever 37, and at its rear end to one arm of the bell crank lever 41, the other arm of which is forked, each arm of the fork being provided with a pin carrying roll, which rolls engage a groove 42 in the clutch disk 43, so as thereby to move the clutch disk 43 out of engagement with the clutch face of the gear 44. This gear 44 through the idler pinion 45 drives the gear 46, which is secured to the auxiliary cam shaft 47, which carries the heddle cams 48. Thus the auxiliary cam shaft 47 is stopped after the cutting of the weft on the left hand side of the loom, and it remains stopped until after the shuttle is replenished with a new bobbin, when the change shaft 32 resumes its original position, thereby again closing the clutch on the cam shaft, and starting the auxiliary cam shaft 47 in motion again, with the result that the shuttle, in its movement from the left hand side of the loom after the second indication of critical exhaustion of the thread, moves through the same shed to the weft replenishing mechanism on the right hand side of the loom that it moves through on its first pick away from the right hand side of the loom back to its position on the left hand side of the loom, as shown in Fig. 1. So the thread is laid in the same shed that it would have been laid in if no replenishment had occurred, but with a motion of the shuttle in the opposite direction through the shed. In the construction shown, the gear 44 is loose on the main cam shaft S, and the clutch member 43 is splined to that shaft. Also, the gear 44 has two-thirds of the number of teeth on the gear 46 on the auxiliary cam shaft, so that the clutch is open one-half revolution of the main cam shaft, or one revolution of the lay shaft, and the auxiliary cam shaft suspends operation for a period of time equal to one revolution of the lay shaft. This arrangement is provided where three heddles are employed, as shown in the drawing.

100 The invention contemplates broadly the stopping of the revolution of the auxiliary cam shaft for a period of time equal to that required for one pick of the shuttle, so that 105

- a shuttle with a severed thread passes from the left hand side of the loom to the right without laying any thread in the shed, and back again in the same shed. The invention 5 may be said, therefore, to contemplate a construction operating to sever the thread close to the shuttle eye on the side of the loom opposite to the weft replenishing mechanism, and to stop the shedding operation 10 of the loom until replenishment on the opposite side of the loom, and the shuttle has been repicked to the first side of the loom, so as thereby to lay a complete intact filling 15 in the same shed as that through which the shuttle passed without laying any filling therein.
- Having thus described the invention, what is claimed is:
1. A feeler loom having, in combination, 20 weft replenishing mechanism, filling feeler mechanism, a filling severing device, a harness motion, means operated by the feeler mechanism on the first indication of critical filling exhaustion for preparing the severing device for operation, and means for actuating the parts having provision for operating the severing device and stopping the harness motion on a succeeding indication of critical exhaustion of the filling.
  2. A feeler loom having, in combination, 30 weft replenishing mechanism on one side of the loom, filling feeler mechanism and a filling severing device on the other side of the loom, a harness motion, and means for actuating the parts having provision for stopping the harness motion and severing the filling on the indication of critical exhaustion of the filling.
  3. A feeler loom having, in combination, 40 weft replenishing mechanism on one side of the loom, filling feeler mechanism and a filling severing device on the other side of the loom, a harness motion, means for operating the parts having provision for stopping the harness motion and severing the filling on the indication of critical exhaustion of the filling, and for starting the harness motion again after replenishment.
  4. A feeler loom having, in combination, 50 weft replenishing mechanism on one side of the loom, filling feeler mechanism and a filling severing device on the other side of the loom, a harness motion, means for actuating the parts having provision for stopping the harness motion and severing the filling on the indication of critical exhaustion of the filling, and starting the harness motion after filling replenishment.
  5. A feeler loom having, in combination, 60 weft replenishing mechanism, filling feeler mechanism for feeling of the filling on the bobbin when it is boxed, a weft severing device located on the same side of the loom as the filling feeler mechanism, a harness motion, means for operating the parts hav-
  - ing provision for severing the outgoing filling close to the eye of the shuttle, stopping the harness motion, replenishing the filling, and starting the harness motion again. 70
  6. A feeler loom having, in combination, 75 weft replenishing mechanism, filling feeler mechanism for feeling of the filling on the bobbin in the shuttle when it is boxed, a weft severing device on the same side of the loom as the filling feeler mechanism, a harness motion, and means for actuating the parts having provision for preparing the severing device for operation upon the first indication of critical exhaustion of the filling, throwing the weft replenishing mechanism into operation, severing the outgoing filling, and stopping the harness motion, on the second indication of critical exhaustion 80 of the filling and thereupon replenishing the filling and starting the harness motion in operation. 85
  7. A feeler loom having, in combination, 90 weft replenishing mechanism on one side of the loom, filling feeler mechanism on the other side of the loom, a filling severing device, connections between the feeler, the severing device and weft replenishing mechanism having provision by virtue of which on the first detection of critical filling exhaustion by the filling feeler, the severing device is prepared to sever the weft, and on the second detection of critical filling exhaustion, the weft is severed and the weft replenishing mechanism is thrown in operation. 95
  8. A feeler loom having, in combination, 100 weft replenishing mechanism on one side of the loom, a filling feeler on the other side of the loom, a weft severing device on the filling feeler side of the loom, a harness motion, and connections between the several devices having provision by virtue of which, upon the first indication of critical exhaustion of the filling, the weft severing device is prepared for operation, and on the second indication of critical exhaustion of the filling the weft is severed near the shuttle, the weft replenishing mechanism is thrown into operation, and the harness motion is thrown out of operation for a period corresponding to one pick of the shuttle. 105
  9. A feeler loom having, in combination, 110 weft replenishing mechanism on one side of the loom, a filling feeler on the opposite side of the loom, a weft severing device on the same side of the loom as the filling feeler, a harness motion, and connections between the several devices having provision on the first indication of critical filling exhaustion to put the weft severing device into condition to operate, and on the second indication of critical filling exhaustion to sever the thread, suspend the operation of the harness motion for the duration of one pick of 115
  - 120
  - 125
  - 130

- the shuttle from the filling feeling side to the weft replenishing side of the loom, and to throw the weft replenishing mechanism into operation.
5. 10. A feeler loom having, in combination, weft replenishing mechanism on one side of the loom, filling feeler mechanism on the other side of the loom, a filling severing device for cutting the running filling on the 10 side opposite the filling replenishing mechanism, a harness motion, means for delaying the operation of the harness motion during one revolution of the crank shaft, means controlled by the feeler to cause the severing device to operate when the shuttle is in the box on the opposite side of the loom from the weft replenishing mechanism next after the indication of filling exhaustion, acting also to control the means for delaying the 20 operation of the harness mechanism so as not to operate on the pick of the shuttle toward the weft replenishing mechanism following severance of the filling, and to cause weft replenishment upon the arrival 25 of the shuttle at the weft replenishing side next following the operation of the filling severing device.
11. A feeler loom having, in combination, weft replenishing mechanism on one side 30 of the loom, a filling severing device on the other side of the loom, a harness motion, means for determining critical exhaustion of filling acting to control the operation of the thread cutter, harness motion and weft 35 replenishing mechanism.
12. A feeler loom having, in combination, weft replenishing mechanism on one side of the loom, filling feeler mechanism and a filling severing device, both on the opposite 40 side of the loom from the weft replenishing mechanism, said filling feeler mechanism causing the operation of the filling severing device and weft replenishing mechanism.
13. A feeler loom having, in combination, weft replenishing mechanism, filling feeler mechanism; a filling severing device, a harness motion, and actuating mechanism operating automatically upon the indication of critical filling exhaustion to cause the severing device to cut the running filling one or more picks prior to filling replenishment, to cause operation of the replenishing mechanism and the opening of the shed by the harness motion in the proper position 50 next succeeding the position of the shed at the time of the severance of the outgoing filling, so as to insure laying the new filling in the shed as called for by the design of the fabric.
14. A feeler loom having, in combination, weft replenishing mechanism, means for determining critical exhaustion of filling, a filling severing device, a harness motion, and actuating mechanism operating 55 automatically to cause the filling severing device to sever the running filling on critical exhaustion thereof, to cause the filling replenishing mechanism to operate after one or more picks following filling severing, 70 having provision to cause the operation of the harness motion in such manner as to weave a continuous pattern of cloth.
15. A feeler loom having, in combination, weft replenishing mechanism on one 75 side of the loom filling feeler mechanism and a filling severing device on the other side of the loom, a harness motion, and connected mechanism operating automatically and successively upon the indication 80 of critical exhaustion of filling to cause the operation of the filling severing device, the suspension of operation of the harness motion, the operation of the weft replenishing mechanism, and the renewal of operation of the harness motion in sequence to weave a 85 continuous pattern of cloth.

CLARE H. DRAPER.
